UNITED STATES PATENT OFFICE.

ARTHUR JOHN ROWLEDGE, OF LONDON, ENGLAND, ASSIGNOR TO D. NAPIER & SON, LIMITED, OF LONDON, ENGLAND.

INTERNAL-COMBUSTION ENGINE.

1,425,057.

Specification of Letters Patent. Patented Aug. 8, 1922.

Application filed November 19, 1917. Serial No. 202,795.

To all whom it may concern:

Be it known that I, ARTHUR JOHN ROWLEDGE, subject of the King of England, residing at London, in England, have invented certain new and useful Improvements in Internal-Combustion Engines, of which the following is a specification.

This invention relates to internal combustion engines of the type comprising three sets or blocks of cylinders arranged so that the axes of the cylinders are disposed in three planes relatively inclined about the crank shaft axis and each block of cylinders having one or a pair of cam shafts mounted on the cylinder heads for operating the valves, and has for its object to effect certain improvements in the method of driving these cam shafts off the crank shaft and also of driving one or more magnetos and the necessary water and oil pumps which is embodied in the present applicant's concurrent application for United States Letters Patent Serial No. 196,710 filed October 15, 1917.

20 The invention will be fully disclosed in the following description when taken in connection with the accompanying drawings in which:

Figure 1 is an end elevation partly in 30 vertical section on the line 1—1 in Figure 3 looking in the direction of the arrows and illustrates one construction of internal combustion engine of the type indicated having the present improvements applied thereto.

35 Figure 2 is an end elevation of the same construction a portion being shown in vertical section taken on the broken line 2—2 in Figure 3.

Figure 3 is a longitudinal vertical section 40 elevation on the line 3—3 of Figure 2 certain parts being omitted for the sake of clearness.

Like letters indicate like parts throughout the drawings.

45 The three sets or blocks of cylinders A, B and C are arranged so that the axes of these cylinders are disposed in three planes relatively inclined about the axis of the crank shaft D the angle between the block of cylinders A and the block of cylinders B being equal to the angle between the block of cylinders A and the block of cylinders C. On the head of each block of cylinders are mounted two cam shafts A' A², B' B² and 55 C' C² these cam shafts serving to operate the

twin sets of valves with which each cylinder in each block is provided. These cam shafts are geared together by spur gearing so that they rotate in opposite directions and on the end of one of the cam shafts A' B' C' is a bevel wheel A³ B³ C³ which gears with a corresponding bevel wheel E' E² mounted on what may be termed the outer end of an intermediate shaft. These three intermediate shafts are similarly constructed and each is divided at some point in its length into two parts connected by a detachable coupling which will be more particularly described hereafter. In Figure 1 the detail construction of the central intermediate shaft only is shown in section the two portions of this shaft being designated G and G'. Of the lateral intermediate shafts H and J only a portion of the end of each shaft appears in Figure 1 the figure 70 showing in elevation the casings K within which these shafts are enclosed.

All the three intermediate shafts G H and J are disposed truly radial with relation to the axis of the crank shaft D. On the end of the lateral intermediate shaft H is a bevel wheel H' and on the end of the intermediate shaft J is a bevel wheel J' both these bevel wheels gearing with a bevel wheel D' mounted on the crank shaft 80 D or on an extension or prolongation thereof. Behind the bevel wheel H' on the lateral shaft H is mounted a second bevel wheel H² which gears with a bevel wheel G² mounted on the end of the central intermediate shaft G. Thus both the lateral intermediate shafts H and J are driven directly from the crank shaft D by means of the crank shaft bevel wheel D' which gears similarly with both the bevel wheels H' and J' while the central intermediate shaft C is driven indirectly from the lateral shaft H through the bevel wheels H² G². The end of the crank shaft is somewhat prolonged or provided with an extension as shown in 90 Figure 3 and carries in addition to the bevel wheel D' a second bevel wheel D² by means of which two magnetos are driven as shown in Figure 2. These two magnetos L are disposed on opposite sides of the crank shaft 100 D and are driven through bevel wheels L' gearing with the bevel wheels D².

The oil and water pumps are driven off the same bevel wheel D' which serves to drive three intermediate shafts G, H and J. 110

A short vertical shaft M with a bevel wheel M' mounted on it and gearing with the bevel wheel D' is disposed radially with relation to the crank shaft axis and opposite to but not truly in line with the central intermediate shaft G as shown in Figures 1 and 3. The water pump N is of suitable type and construction and is mounted on or driven either directly or indirectly by or through the shaft M. At some suitable point in the length of the pump shaft M is mounted a skew pinion M² or a worm which gears with two corresponding wheels O each of which is fixed 10 on a shaft O' which lies at right angles to the pump shaft M and parallel to the axis of the crank shaft D. Each of these shafts O' drives two coaxially mounted oil pumps P Q arranged preferably in casings R and R' which adjoin each other and may be formed integral. Thus the crank shaft D drives directly the water pump shaft M and through this shaft M drives indirectly four oil pumps arranged in pairs tandem- 15 wise the drive being taken off the crank shaft from the bevel wheel D' which serves to drive the three intermediate shafts G, H and J.

One of the oil pumps P in each pair 20 serves to deal with the oil which drains into a sump suitably disposed below, the suction pipes P² from this sump being shown in Figure 2. These two pumps P deliver through a pipe P³ to the oil tank. The 25 other pump Q on each oil pump shaft O' serves to supply oil to the engine this oil being drawn from the tank through a lateral connection Q' (Figure 2) and delivering upwards. The delivery from one of 30 these supply pumps Q leads as at Q² (Figure 3) into one end of the hollow crank shaft D which is carried out to a point over or adjacent to the oil pumps. A second delivery Q³ (Figure 2) from the supply 35 pump Q leads to the opposite end of the crank shaft. The other supply pump Q delivers through a connection Q⁴ to the cam shafts on the heads of the cylinders.

The coupling employed for the purpose 40 of connecting the abutting ends of the two parts of each intermediate shaft, such as the two parts G G' of the central intermediate shaft, may conveniently be constructed in the following manner and as illustrated in Figure 1. Though as there shown 45 in connection with the central shaft G G' it is to be understood that a similar device may be employed for coupling the two portions comprising each lateral intermediate 50 shaft H and J.

The two abutting ends of the shaft 55 lengths G and G' are somewhat thickened and in each thickened part are formed one or more longitudinal keyways G³ G⁴. In 60 each of these key-ways lies a correspond-

ing key or feather S carried by a sleeve S' which surrounds the joint. The key-ways G³ extend to a greater distance along the shaft section G than the keyways G⁴ extend along the end of the shaft length G'. Thus 70 while sliding movement of the sleeve S' together with the keys S along the shaft length G' in the outward direction away from the crank shaft is limited, so that the keys can only partially pass beyond the 75 joint between the ends of the shaft portions G and G', on the other hand the sleeve S' together with the keys S may be slid along the shaft length G in the direction of the crank shaft until the sleeve and the keys 80 are wholly clear of the abutting ends of the shaft lengths G and G'. When the sleeve S' occupies this latter position it is possible to separate the ends of the shaft lengths G and G' and the outer portion G' 85 can be independently rotated or removed. To make the joint the ends of the two portions G G' of the shaft are brought together and the sleeve S' is then slipped over them when the keys S will engage equally 90 the key-ways G³ and G⁴ and thus serve to couple the ends of the shaft lengths so as to transmit the drive. The sleeve S' is retained in place by a bolt or pin S² which passes transversely through the sleeve and 95 through the abutting ends of the shaft lengths G and G' circular notches being formed in the ends of these shaft lengths to allow of the passage of the bolt. The bolt S² thus also helps to lock the ends of the shaft 100 lengths together. The sleeve S' is carried externally in a cylindrical guide or bearing S³ which is in turn mounted in a boss K' which forms part of the casing enclosing 105 the intermediate shaft. Access can be had 110 to the coupling by unscrewing a socket or sleeve K² which encloses the coupling this sleeve being then free to be slid along the tubular casing K.

By thus forming each intermediate shaft 110 in two portions connected by a device such as described or by some other adjustable coupling of a like nature it is possible to set the timing of the cam shafts carried on the cylinder heads after the parts have been 115 assembled. Thus when the cylinders are in place the shaft length G' can be rotated to adjust the timing of the cam shafts A' A² before the shaft length G' is coupled to the shaft length G.

The disposition of the parts and details of construction may be modified as found desirable and in accordance with the construction of the other portions of the engine.

What I claim as my invention and desire to secure by Letters Patent is:—

1. In an internal combustion engine, in combination, a crank shaft having a bevel wheel fixed thereon, a rotary oil pump hav-

ing a rotatable shaft parallel to said crank shaft, a rotary water pump having a shaft parallel to said crank shaft, and adjacent the shaft of the oil pump, and means for 5 driving said pumps from said crank shaft, said means comprising a short shaft arranged with its axis radial to the axis of said crank shaft and having a bevel wheel mounted thereon which meshes with the 10 bevel wheel on the crank shaft, said shaft extending between the pump shafts and being operatively connected thereto.

2. In an internal combustion engine the 15 combination of three blocks of cylinders arranged so that the axes of the cylinders lie in three planes relatively inclined about the crank shaft axis, a cam shaft mounted on the head of each block of cylinders, a bevel wheel on one end of each cam shaft, a crank 20 shaft, a bevel wheel towards one end of the crank shaft and driven thereby, a second bevel wheel adjacent to the first bevel wheel and similarly driven by the crank shaft, three intermediate shafts through which the 25 cam shafts are driven from the crank shaft all these three shafts lying truly radial with relation to the crank shaft axis, a bevel wheel on the outer end of each intermediate shaft gearing with the bevel wheel on the 30 end of the corresponding cam shaft, a bevel wheel on the inner end of each lateral intermediate shaft these two bevel wheels gearing with the first bevel wheel on the crank shaft, a second bevel wheel on one of the 35 lateral intermediate shafts and positioned near its inner end, a bevel wheel on the inner end of the central intermediate shaft 40 this bevel wheel gearing with the second bevel wheel on the lateral intermediate shaft, two magnetos each having on its shaft a bevel wheel which gears with the second bevel wheel on the crank shaft, oil and water 45 pumps, and means for driving these pumps off the first bevel wheel on the crank shaft as set forth.

3. In an internal combustion engine the 50 combination of three blocks of cylinders arranged so that the axes of the cylinders lie in three planes relatively inclined about the crank shaft axis, a cam shaft mounted on the head of each block of cylinders, a bevel wheel on one end of each cam shaft, a crank shaft, a bevel wheel towards one end of the crank shaft and driven thereby, three intermediate shafts through which the cam 55 shafts are driven from the crank shaft all these three shafts lying truly radial with relation to the crank shaft axis, a bevel wheel on the outer end of each intermediate shaft gearing with the bevel wheel on the 60 end of the corresponding cam shaft, a bevel wheel on the inner end of each lateral intermediate shaft these two bevel wheels gearing with the bevel wheel on the crank shaft, a second bevel wheel on one of the lateral intermediate shafts and positioned near its inner end, a bevel wheel on the inner end 65 of the central intermediate shaft this bevel

wheel gearing with the second bevel wheel on the lateral intermediate shaft, oil and water pumps, and means for driving these pumps off the bevel wheel on the crank shaft as set forth. 70

4. In an internal combustion engine the combination of three blocks of cylinders arranged so that the axes of the cylinders lie in three planes relatively inclined about the crank shaft axis, a cam shaft mounted on the head of each block of cylinders, a bevel wheel on one end of each cam shaft, a crank shaft, a bevel wheel towards one end of the crank shaft and driven thereby, a second bevel wheel adjacent to the first bevel wheel and similarly driven by the crank shaft, three intermediate shafts through which the cam shafts are driven from the crank shaft all these three shafts lying truly radial with relation to the crank shaft axis, a bevel wheel on the outer end of each intermediate shaft 80 gearing with the bevel wheel on the end of the corresponding cam shaft, a bevel wheel on the inner end of each lateral intermediate shaft these two bevel wheels gearing with the first bevel wheel on the crank shaft, a second bevel wheel on one of the lateral intermediate shafts and positioned near its inner end, a bevel wheel on the inner end of the central intermediate shaft 85 this bevel wheel gearing with the second bevel wheel on the lateral intermediate shaft, two magnetos each having on its shaft a bevel wheel which gears with the second bevel wheel on the crank shaft, oil and water 90 pumps, and means for driving these pumps off the first bevel wheel on the crank shaft as set forth. 95

5. In an internal combustion engine the combination of three blocks of cylinders arranged so that the axes of the cylinders lie in three planes relatively inclined about the crank shaft axis, two cam shafts mounted on the head of each block of cylinders, gearing between the two cam shafts on each block of cylinders, a bevel wheel on one end of one of the cam shafts in each pair, a crank shaft, a bevel wheel towards one end of the crank shaft and driven thereby, a second bevel wheel adjacent to the first bevel wheel and similarly driven by the crank shaft, three intermediate shafts through which the cam shafts are driven from the crank shaft all these three shafts lying truly radial with relation to the crank 100 shaft axis, a bevel wheel on the outer end of each intermediate shaft gearing with the bevel wheel on the end of the corresponding cam shaft, a bevel wheel on the inner end of each lateral intermediate shaft these two bevel wheels gearing with the first bevel wheel on the crank shaft, a second bevel wheel on one of the lateral intermediate shafts and positioned near its inner end, a bevel wheel on the inner end of the central intermediate shaft these two 105 bevel wheels gearing with the first bevel wheel on the crank shaft, a second bevel wheel on one of the lateral intermediate shafts and positioned near its inner end, a bevel wheel on the inner end of the central intermediate shaft this bevel 110

intermediate shaft this bevel wheel gearing with the second bevel wheel on the lateral intermediate shaft, two magnetos each having on its shaft a bevel wheel which gears 5 with the second bevel wheel on the crank shaft, oil and water pumps, and means for driving these pumps off the first bevel wheel on the crank shaft as set forth.

6. In an internal combustion engine the 10 combination of three blocks of cylinders arranged so that the axes of the cylinders lie in three planes relatively inclined about the crank shaft axis, a cam shaft mounted on the head of each block of cylinders, a bevel 15 wheel on one end of each cam shaft, a crank shaft, a bevel wheel towards one end of the crank shaft and driven thereby, three intermediate shafts through which the cam shafts are driven from the crank shaft all 20 these three shafts lying truly radial with relation to the crank shaft axis, a bevel wheel on the outer end of each intermediate shaft gearing with the bevel wheel on the end of the corresponding cam shaft, a bevel 25 wheel on the inner end of each lateral intermediate shaft these two bevel wheels gearing with the bevel wheel on the crank shaft, a second bevel wheel on one of the lateral intermediate shafts and positioned 30 near its inner end, a bevel wheel on the inner end of the central intermediate shaft this bevel wheel gearing with the second bevel wheel on the lateral intermediate shaft, a water pump with its shaft disposed at right angles to the crank shaft axis, a bevel wheel on the end of the water 35 pump shaft gearing with the bevel wheel on the crank shaft, oil pumps, and means for driving the oil pumps off the water pump shaft as set forth.

7. In an internal combustion engine the combination of three blocks of cylinders arranged so that the axes of the cylinders lie in three planes relatively inclined about 45 the crank shaft axis, a cam shaft mounted on the head of each block of cylinders, a bevel wheel on one end of each cam shaft, a crank shaft, a bevel wheel towards one end of the crank shaft and driven thereby, 50 three intermediate shafts through which the cam shafts are driven from the crank shaft all these three shafts lying truly radial with relation to the crank shaft axis, a bevel wheel on the outer end of each intermediate shaft gearing with the bevel wheel on the end of the corresponding cam shaft, a bevel 55 wheel on the inner end of each lateral intermediate shaft these two bevel wheels gearing with the bevel wheel on the crank shaft, a second bevel wheel on one of the lateral intermediate shafts and positioned 60 near its inner end, a bevel wheel on the inner end of the central intermediate shaft this bevel wheel gearing with the second bevel wheel on the lateral intermediate shaft, a water pump with its shaft disposed at right angles to the crank shaft axis, a bevel wheel on the end of the water 65 pump shaft gearing with the bevel wheel on the crank shaft, oil pumps, and means for driving the oil pumps off the water pump shaft as set forth.

mediate shaft, a water pump with its shaft disposed at right angles to the crank shaft axis, a bevel wheel on the end of the water pump shaft gearing with the bevel wheel on the crank shaft, two sets of oil pumps 70 on two shafts disposed parallel to the crank shaft axis, and gearing between the two oil pump shafts and the water pump shaft so that the oil pumps are driven off the water pump shaft as set forth.

8. In an internal combustion engine the combination of three blocks of cylinders arranged so that the axes of the cylinders lie in three planes relatively inclined about the crank shaft axis, a cam shaft mounted 80 on the head of each block of cylinders, a bevel wheel on one end of each cam shaft, a crank shaft, a bevel wheel towards one end of the crank shaft and driven thereby, a second bevel wheel adjacent to the first 85 bevel wheel, and similarly driven by the crank shaft, three intermediate shafts through which the cam shafts are driven from the crank shaft all these three shafts lying truly radial with relation to the crank 90 shaft axis and each of these shafts being divided at some point in its length into two parts the ends of which abut, a detachable coupling for the abutting ends of the two parts of each intermediate shaft, a bevel 95 wheel on the outer end of each intermediate shaft gearing with the bevel wheel on the end of the corresponding cam shaft, a bevel wheel on the inner end of each lateral intermediate shaft these two bevel wheels gearing with the first bevel wheel on the crank shaft, a second bevel wheel on one of the lateral intermediate shafts and positioned 100 near its inner end, a bevel wheel on the inner end of the central intermediate shaft this bevel wheel gearing with the second bevel wheel on the lateral intermediate shaft, two magnetos each having on its shaft a bevel 105 wheel which gears with the second bevel wheel on the crank shaft, oil and water pumps, and means for driving these pumps off the first bevel wheel on the crank shaft as set forth.

9. In an internal combustion engine the combination of three blocks of cylinders arranged so that the axes of the cylinders lie 110 in three planes relatively inclined about the crank shaft axis, two cam shafts mounted on the head of each block of cylinders, gearing between the two cam shafts on each block of cylinders, a bevel wheel on one end of one of the cam shafts in each pair, a crank shaft, a bevel wheel towards one end of the crank shaft and driven thereby, a second bevel wheel adjacent to the first bevel wheel and similarly driven by the crank shaft, three intermediate shafts through which the cam shafts are driven from the crank shaft 115 all these three shafts lying truly radial with relation to the crank shaft axis and each of these shafts being divided at some point in 120

125

130

its length into two parts the ends of which abut, a detachable coupling for the abutting ends of the two parts of each intermediate shaft, a bevel wheel on the outer end of each 5 intermediate shaft gearing with the bevel wheel on the end of the corresponding cam shaft, a bevel wheel on the inner end of each lateral intermediate shaft these two bevel wheels gearing with the first bevel wheel on 10 the crank shaft, a second bevel wheel on one of the lateral intermediate shafts and positioned near its inner end, a bevel wheel on the inner end of the central intermediate shaft this bevel wheel gearing with the second bevel wheel on the lateral intermediate shaft, two magnetos oppositely disposed on either side of the crank shaft with their 15 shafts at right angles to the crank shaft axis, a bevel wheel on the end of each mag-

neto shaft which gears with the second bevel 20 wheel on the crank shaft, a water pump with its shaft disposed at right angles to the crank shaft axis, a bevel wheel on the end of the water pump shaft gearing with the first bevel wheel on the crank shaft, two sets 25 of oil pumps on two shafts disposed parallel to the crank shaft axis, and gearing between the two oil pump shafts and the water pump shaft so that the oil pumps are driven off the water pump shaft as set forth. 30

In testimony whereof I have signed my name to this specification in the presence of two subscribing witnesses.
